JOHN G. SHODRON, OF FORT ATKINSON, WISCONSIN, ASSIGNOR TO JAMES MANUFACTURING COMPANY, OF FORT ATKINSON, WISCONSIN, A CORPORATION OF WISCONSIN

JOIST BEARING PLATE AND ANCHOR

Application filed August 22, 1928. Serial No. 301,205.

This invention relates to improvements in a joist bearing plate and anchor.

It is the primary object of the invention to provide a bearing plate and anchor suitable for supporting and fixing the position of a joist with reference to a masonry wall made of hollow building block, such, for example, as hollow clay tile. It is my purpose to provide for distributing the weight of the joist 10 and the parts supported thereby upon several load carrying webs of the hollow tile, while anchoring the joist against longitudinal displacement with reference to the wall.

In achieving these results, I propose to provide a plate which is relatively thin and is receivable into the mortar space in the wall, such plate having wall engaging prongs adapted to interact with webs of the hollow tile blocks of the wall and a means likewise 20 adapted to interact with the joist itself. It is my further purpose to design the last mentioned means in such a way that if the joist should become burned through or broken in a fire or other accident, it would disengage 25 itself from the securing means fixing it to the anchor and would fall without destroying the wall.

In the drawings—

Figure 1 is a perspective view of a fragment of wall showing my improved bearing plate and joist anchor in place therein;

Figure 2 is an enlarged detail in perspective of the bearing plate and joist anchor per se.

Like parts are identified by similar reference characters throughout the several views.

This application is a companion of my co-pending application, executed August 22nd, 1928, and entitled Load bearing tile. The tile 40 herein disclosed is the same as the tile to which such application relates and the bearing plate and joist anchor which forms the subject matter of this application is incidentally disclosed in the companion case.

While it is not essential to this invention that the tile of the wall should be of the special form illustrated in my companion application above referred to, it will nevertheless be obvious that such form of tile lends 50 itself to the use of this bearing plate and

anchor with advantage. The individual tile are shown at 5 and it will be observed that they are provided with end opening recesses at 6 which are complementary to form a cell similar to the cells 7 and 8 into which the tile 5 is divided by means of its variously disposed internal webs and partitions. Access to the cell formed by the juxtaposition of recesses 6 is had by breaking away the inner wall and adjacent web 9 and 10 of the contiguous ends of tile 5 at the point where the joist is to come. The end of the joist 11 is beveled, as shown at 12, and projects into the complementary recesses 6 through the opening thus formed.

It will be obvious from a study of the exposed upper surface of the tile 5 that if the joist were allowed to bear directly upon such central portions of the underlying tile as might be engaged by its extremity there would be a severe load upon a very few webs therebeneath. It is the primary function of the bearing plate 15 to distribute the load and to this end the plate is made sufficiently broad so that it rests upon several webs of the tile including particularly the webs 16, 17, 18, and partition 10 and wall 9. It will be obvious, therefore, that the bearing plate 15 will underlie the whole of the combined recesses 6 into which the joist projects.

The bearing plate is held in position not only by means of the mortar in which it is seated and by means of the tile and the joist resting thereon but is also held positively by means of downwardly turned lugs 20 which engage behind the central longitudinal partition web 18 of the tile and at either side of the transverse webs 21 and 22 at the outer side of the tile. The joist is notched at 23 and the anchor plate 15 is provided with an upstanding flange at 25 which is engaged in notch 23 and thereby rigidly fixes the joist against any tension strains tending to withdraw it from the recess into which its end is placed.

In many fires and other disasters it is found that the joists either break or burn or the support for their inner ends is destroyed with the result that the load upon the joist and the parts still connected therewith tend

to draw the joist toward the center of the burning building as it swings downwardly. In such cases the positive connection of the joist with the wall adds to the disaster since the load upon the joist frequently pulls the wall inwardly as the joist falls. It will be observed that in the practice of this invention the beveled extremity 12 of the joist leaves the joist free of superimposed portions of the wall and makes it possible for the joist in falling to unhook itself from the short flange 25 after it has swung through a substantial arc in falling. It can be demonstrated that in practice this structure relieves the wall of the tension strains which tend to destroy it when the wooden portions of the building structure are destroyed.

It will be seen from the foregoing disclosure that I have provided means for supporting and anchoring a joist in a tile wall, while providing for the freeing of the joist from its anchoring means if the inner end of the joist falls.

I claim:

1. A plate adapted for use between courses of a tile wall for the support of a joist, such plate being of greater width than the joist whereby to obtain anchorage between courses of tile, having an area adapted to span the space between a plurality of longitudinal and transverse webs of the tile comprising the wall, and being provided with tile engaging lugs complementary to the webs of the tile used in the wall for interaction therewith, whereby to fix the position of the plate against withdrawal from the wall, and means for securing a joist against displacement longitudinally of said plate.

2. The combination with load bearing tile provided with a plurality of longitudinally extending webs along the inner face of the tile and transversely extending webs, of a bearing plate spanning said longitudinally extending webs and certain of said transverse webs and adapted to distribute load therebetween, means carried by said plate positioned for engagement with certain of the longitudinal and transverse webs of the tile on which said plate rests, a joist, and means for securing said joist against longitudinal displacement with reference to said plate.

3. The combination with load bearing tile provided with longitudinally and transversely extending webs, of a bearing plate spanning certain of said webs and adapted to distribute load therebetween, means carried by said plate positioned for engagement with certain of the webs of the tile on which said plate rests, a joist, and means for securing said joist against longitudinal displacement with reference to said plate, said plate being of greater width than the joist and having its side margins interposed between superposed tile.

4. The combination with a wall comprising load bearing tile having longitudinal and transverse webs, certain of which provide a cell accessible from the interior of said wall, a joist projecting into said cell, and a bearing plate interposed between superposed courses of said tile and underlying substantially all of said cell whereby to support and distribute the weight of said joist from the underlying tile, said underlying tile having parallel longitudinally extending webs near its inner face in supporting relation to the plate, and a more distant longitudinally extending web in anchoring relation to the plate and connected with the inner webs by a transverse partition, also in supporting relation to the plate.

5. The combination with a tile wall having load bearing tile provided with supporting webs concentrated along the inner face of the tile, said wall having the tile of one course spaced apart to provide a joist receiving recess, of a joist supporting plate having its side margins interposed between tile at the sides of said recesses in the plane of the bottom thereof, said plate having its inner margin in anchoring engagement with the supporting tile at the sides of said recesses and having its inner margin provided with a central upward extension for anchoring engagement with a joist, said extension and said flanges being adapted to prevent relative movement of the plate and joist along the axial line of the joist.
